(57) CLAIM

The ornamental design for a table lamp, as shown and described.

DESCRIPTION

FIG. 1 is a front elevational view of a table lamp showing my new design.

The boxes and inscribed text which are shown in broken lines boxes are for illustrative purposes only and forms no part of the claimed design.

FIG. 2 is a right side elevational view thereof, the left side being a mirror image;

FIG. 3 is a rear elevational view thereof; and,

FIG. 4 is a top plan view thereof.

The bottom of the table lamp is flat and unornamented.
